LUGGAGE CARRIER ATTACHED TO THE
BACK-WHEEL STAYS OF CYCLESJules Bachmann, Dubendorf, Switzerland, as-
signor to Max Schneider, Zurich, SwitzerlandApplication July 9, 1948, Serial No. 37,825
In Switzerland July 1, 1947

2 Claims. (Cl. 224—32)

1

The present invention relates to a luggage carrier attached to the back-wheel stays of push bicycles and motor bicycles. According to the invention, side flaps are provided hanging on both sides of the horizontal support which is known per se and serves to carry luggage; these side flaps can be swung up to the level of the said support. Each side flap has preferably two swivellingly supported arms, each of which is connected to two fitting surfaces arranged at right angles to each other, and on these surfaces springs act in such a manner that the side flaps are held in the horizontal or vertical position.

One execution of the object of the invention is illustrated by way of example in the accompanying drawing, in which:

Fig. 1 is a perspective view of the luggage carrier;

Fig. 2 a cross-section on the line II—II of Fig. 1, and

Fig. 3 a section on the line III—III of Fig. 2.

Fig. 4 is a perspective view of the luggage carrier with the side flaps raised up.

The new luggage carrier has a main or primary supporting frame 2, known per se, arranged for attaching to the fork 1 of the back wheel, and having a horizontal part 2a on which objects can be laid. Further, on the primary frame 2 a hinged clamping piece 4 is fitted in known manner, standing under the influence of a torsion spring 3. On the two stays forming the part 2a, two traverses 5 are arranged, in each of which a flat spring 6 is fixed. Two rotatable cams 7 are pivotably supported on bolts 8 in each traverse 5. Each of the rotatable cams 7 has two fitting surfaces 9, 9a slightly bent inwards and standing at right angles to each other; on them lie the ends of the springs 6. By means of the said rotatable cams, side or secondary supporting frames 10 are swivellingly supported in the traverses 5. Each side flaps has two arms 11, each of which is firmly connected to a rotatable piece 7. To each of the secondary frames 10 a frame-shaped holder 12 is hinged and stands under the influence of a torsion spring 13. The latter tends to press the upper part of the holder 12 on to the arms 11; i. e. an object laid between them will be held firmly clamped, fluted rubber rollers 14 being also fixed on the holder to ensure a better hold for the object in question. Also the rubber rollers 15 will make it more difficult for objects firmly clamped between the holder 12 and the arms 11 to be unintentionally displaced. With the secondary frames 10 in the depending vertical position (Fig. 1), objects can

2

be firmly held independently in the two secondary frames and also under the clamp 4. The springs 6 are chosen of such strength, and the pressure of the spring ends on the fitting surfaces 9 are chosen so strong, that the side flaps 10 cannot swing unintentionally round the bolts 8.

But if the secondary frames 10 are turned up through 90°, they come to lie in the horizontal position. The springs 6 then press on to the fitting surfaces 9a and hold the side flaps in the horizontal position as illustrated in Fig. 4. The arms 11 and the part 2a now lie in one plane, so that comparatively large objects, such as attaché cases, etc. are supported on a practically even surface and do not sag downwards on both sides of the clamp 4.

What I claim as my invention and desire to secure by Letters Patent is:

1. A luggage carrier for cycles comprising, a primary supporting frame adapted to be attached to the rear fork of the cycle, said primary supporting frame including two spaced substantially parallel parts extending rearwardly and horizontally when said frame is attached to said fork, two secondary supporting frames each comprising two parallel arms of angular shape pivotally attached with one of their ends to said parallel parts of said primary supporting frame to project laterally therefrom, cooperating means on said primary supporting frame and on said arms for retaining said secondary supporting frames selectively in two positions, one of said two positions constituting a folded position in which said secondary supporting frames depend vertically downward and the other position constituting an unfolded position in which said secondary supporting frames project horizontally outward and in which said arms are positioned substantially in the same plane as said spaced parallel parts of said primary supporting frame, said angular shaped arms being arranged in such manner that the ends thereof opposite the ones pivotally connected to said primary supporting frame are directed vertically upward when said secondary supporting frames are retained in their unfolded position, said last named ends of said arms being connected with each other by a transverse member extending parallel to the pivot axis of said angular shaped arms, a frame-shaped holder pivotally mounted on said transverse member, and spring means mounted on said transverse member, and operatively connected with said holder to yieldably urge the same in a direction towards said angular shape arms, whereby the carrier forms a three-sided en-

closed apparatus especially designed for large packages when said secondary supporting frames are retained in their unfolded position, and whereby said carrier forms a multiple compartmentalized structure when said secondary supporting frames are retained in their folded position.

2. A luggage carrier for cycles comprising, a primary supporting frame adapted to be attached to the rear fork of the cycle, said primary supporting frame including two spaced substantially parallel parts extending rearwardly and horizontally when said frame is attached to said fork, two secondary supporting frames each comprising two parallel arms of angular shape pivotally attached with one of their ends to said parallel parts of said primary supporting frame to project laterally therefrom, cams fixedly secured to said ends of said arms, spring means secured to said primary supporting frame and engaging said cams whereby said secondary supporting frames are adapted to be adjusted and retained selectively in two positions, one of said two positions constituting a folded position in which said secondary supporting frames depend vertically downward and the other position constituting an unfolded position in which said secondary supporting frames project horizontally outward and in which said arms are positioned substantially in the same plane as said spaced parallel parts of said primary supporting frame, said angular shape arms being arranged in such manner that the ends thereof opposite the ones pivotally connected to said primary supporting frame are directed vertically upward when said secondary supporting frames are retained in their unfolded position, said last named ends of said arms being connected with each other by a trans-

5
10
15

verse member extending parallel to the pivot axis of said angular shape arms, a frame-shaped holder pivotally mounted on said transverse member, and spring means mounted on said transverse member and operatively connected with said holder to yieldably urge the same in a direction towards said angular shape arms, whereby the carrier forms a three-sided enclosed apparatus especially designed for large packages when said secondary supporting frames are retained in their unfolded position, and whereby said carrier forms a multiple compartmentalized structure when said secondary supporting frames are retained in their folded position.
